UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMPUTING-MACHINE.

1,271,254.

Specification of Letters Patent.

Patented July 2, 1918.

Application filed July 28, 1910. Serial No. 574,223.

To all whom it may concern:

Be it known that I, WALTER WRIGHT, a citizen of the United States, residing in New York, in the county of New York and State 5 of New York, have invented certain new and useful Improvements in Computing-Machines, of which the following is a specification.

This invention relates to computing machines, as disclosed in co-pending application No. 554,452, filed April 9, 1910, and in co-pending application No. 543,603, filed jointly by Gustave O. Degener and myself, February 12, 1910, in which the computing 10 wheels are power-driven, while the extent of their rotation is controlled by a set of numeral keys, which operate an escapement mechanism that is connected to the computing-wheel train.

20 The movement of the escapement wheel and the computing wheel train in very quick, and the impetus gathered by said wheel and said train is very great, especially where the movement is considerable, as for instance in adding "8" or "9". The sudden arrest of the rapidly moving train tends to make the machine noisy, and also to make the parts wear rapidly.

25 The principal object of the present improvements is to overcome these objections, and to this end I connect to the computing wheel train, at a suitable point, a centrifugally acting brake, which serves to prevent unduly rapid rotation of the escapement 30 wheel and other parts.

In the accompanying drawings,

Figure 1 is a side elevation, partly in section, of the present improvements applied to a combined computing and typewriting machine, as shown in said pending applications.

Fig. 2 is a sectional side elevation of the brake mechanism.

Fig. 3 is a sectional plan of the invention.

Fig. 4 is a perspective view of the same.

So far as the present improvements are concerned, the escapement or index wheel may be controlled in a variety of ways. For the sake of illustration, there is shown in 50 the drawings a controlling mechanism which is disclosed in my pending United States application No. 554,452, filed April 9, 1910, and which in many respects is substantially

like my Patent No. 1,162,730, dated November 30, 1915, although this mechanism forms 55 no part of the present invention.

Keys 1 are mounted on levers 2, which by means of links 3 operate bell cranks 4; and the latter, through links 5, rock the levers 6, the latter having on their ends cams 7 to 60 swing and engage escapement pins 8, to cause the latter to project from an index or valuating wheel 9, on which they are mounted; a band coiled spring 10 surrounding the circular set of index pins which serve as escapement members, and engaging grooves 11 in said pins to hold the latter in either normal or projected positions.

As also set forth in said applications and patent, the projected index or escapement pin 8 engages a pinion 12, which is fixed to a secondary escapement wheel 13, the latter controlled by dogs 14, 15. The inner end of each of the levers 6 operates a universal disk 16, which rocks a lever 17, and 70 through a link 18 and arm 19 rocks a shaft 20, upon which the dogs 14, 15 are fixed; the parts being returned to normal positions by a spring 21 coiled about a stem 22 upon which the universal disk 16 is mounted. 80

The key levers 2 are connected at 23 to bell cranks 24, which swing type bars 25 upwardly and rearwardly to strike a platen 26, as is usual in the Underwood typewriting machine illustrated.

The power to drive the adding wheels is supplied by a constantly revolving motor 27, which, by means of any suitable brake or friction clutch connection produces a constant torque, upon a shaft 28. This may 90 be done by means of a centrifugal brake or clutch 29 working in a friction ring 30 carried by said shaft 28. To the latter is connected by gears 31 and 32 a shaft 33, which carries at one end a bevel pinion 34, meshing with a bevel pinion 35, the latter fixed upon a gear 36 which meshes with a pinion 37 upon a shaft 38 which carries the index or escapement wheel 9.

Also meshing with the pinion 35 is a bevel 100 pinion 39, upon a horizontal shaft 40, connected by bevel pinions 41, 42, with a vertical drive shaft 43 for the adding wheels. At its upper end, said drive shaft 43 carries a bevel pinion 44, to mesh with a bevel pinion 45 upon a horizontal shaft 46, which 105

carries a master-wheel 47 for engagement with any of a series of internally toothed wheels 48, the latter also having teeth 49 on their outer peripheries, to engage gears 50 secured upon computing wheels 51. Wheels 48, 50 and 51 are mounted on a carriage 52 connected by an arm 53 to the letter-feeding carriage 54 of the typewriting machine, so that the master-wheel 47 may act 5 consecutively upon the gears 48, as the keys 1 are operated to print the figures and feed the carriage 54. It will be seen from the foregoing, that whenever any key 1 is depressed, the dogs 14, 15 are rocked and the 10 secondary escapement wheel 13 is permitted to escape, and the previously projected index or escapement pin 8 slips past the pinion 12, permitting the index wheel 9 to rotate until the newly set index pin 8 comes 15 into engagement with the pinion 12, bringing the next arm on the secondary escapement wheel 13 into engagement with the dog 14, which will prevent further rotation of the index or valuating wheel 9. This gives 20 an extent of rotation of the index or valuating wheel 9, and hence of the master wheel 47, corresponding with the value of the numeral key 1 struck. The features above described in detail form no part of the present invention, but are described and claimed 25 in said patent and pending applications.

While I show the present improvements in connection with the above-described train of power-driven escapement wheels, still it 30 will be understood that they may be applied to other forms of escapement wheels for computing devices.

Within a cup or depression 55, preferably 35 formed in the index wheel 9, plays a brake comprising segments or weights 60, carried on spring arms 61, the latter fixed upon a hub 62 which is loose upon the shaft 38 of the escapement or index wheel 9. To said hub is fixed a pinion 63, which is driven by 40 a gear 64, the latter fixed upon a shaft 65 having at its other end a bevel pinion 66 to mesh with a bevel pinion 67 on the shaft 40. The described train of gearing causes 45 the hub 62, carrying the brake segments 60, to rotate in the opposite direction from the index wheel 9.

Owing to the provision of the movement multiplying gearing 64, 63, the segments 60 are caused to rotate very rapidly during the 50 rotation of the index or escapement wheel 9 and the computing-wheel train, and the segments or shoes 60 fly out and engage the inner wall of the cup-like depression 55 in the escapement wheel, and act as a brake to retard the rotation of the latter. The parts 55 may be so proportioned that this retarding effect is not felt until the escapement wheel 60 acquires a high speed of rotation, so that when small numbers, such as "1" and "2" are added, the index or escapement wheel 65 rotates only a little, and the braking effect

is not noticeable; but when larger numbers are added the brake takes effect and checks the revolving escapement wheel, and prevents it from acquiring too high speed. This checking action occurs during the latter part 70 of the rotation of the escapement wheel, so that speed of operation is preserved, while the noise is reduced and the wear upon the gears and escapement devices is lessened.

Variations may be resorted to within the 75 scope of the invention, and portions of the improvements may be used without others.

Having thus described my invention, I claim:

1. In a computing machine, the combination 80 with a power-driven train of rotary computing mechanism, including an escapement wheel and key-operated devices to control said escapement wheel, of a member connected to said train of computing mechanism to revolve in opposition to said escapement wheel, and having a centrifugally-operating brake to engage said escapement wheel.

2. In a computing machine, the combination 85 with a power-driven train of rotary computing mechanism, including an escapement wheel and key-operated devices to control said escapement wheel, of a centrifugally-operating brake to engage said escapement 90 wheel, and movement-multiplying gearing connecting said train to said brake to cause the latter to rotate in opposition to said escapement wheel at all movements of the latter.

3. In a computing machine, the combination 95 with a train of rotary computing mechanism, including a drive shaft, and an escapement wheel geared to said drive shaft, of key-operated means to control said escapement wheel, a gear connected to said drive shaft, a pinion meshing with said gear, and a centrifugal brake to bear upon said escapement wheel and connected to said pinion to be rotated at higher speed than said drive 100 shaft and in the opposite direction from said escapement wheel.

4. In a computing machine, the combination 105 with a train of rotary computing mechanism, including a drive shaft, and an escapement wheel geared to said drive shaft, of key-operated means to control said escapement wheel, a gear connected to said drive shaft, a pinion meshing with said gear, and a centrifugal brake to bear upon said escapement wheel and connected to said pinion to be rotated at higher speed than said drive 110 shaft and in the opposite direction from said escapement wheel, the latter having a cup portion within which said brake 115 works.

5. In a computing machine, the combination 120 with a train of computing mechanism, of a rotary escapement wheel therefor checked by a brake revolving in the opposite 125 130

direction only when the wheel reaches a high speed of rotation, but operating without opposition from the brake for short movements of the wheel, the brake being constantly driven by said train during all movements of the latter.

6. In a computing mechanism, the combination with a variably movable power-driven key controlled index wheel movable 10 always in one direction, variable amounts of intermittently operated means dependent upon the movement of said wheel for checking the latter only at the major movements thereof.

15 7. In a computing machine, a set of computing wheels, an index wheel variously movable to determine the amount of operation of said computing wheels, a shaft on which the index wheel is mounted, a pinion

20 on said shaft by which the index wheel is driven, a gear having a connection to said pinion, a second pinion in mesh with said gear and loose on said shaft, and a centrifugal braking device connected to the second 25 pinion to be rotated thereby in an opposite direction from said index wheel.

8. An index wheel having a hollow on each side, one to surround the bearing in which it revolves, and the other to receive 30 a centrifugal brake and having a perforated periphery for the index pins.

9. The combination of an index wheel, key-controlled means for operating the same, a source of power for rotating said 35 wheel, said wheel having a cup or depression, a centrifugal brake rotating in said cup or depression, a pinion connected to said brake, and a movement-multiplying gear meshing with said pinion and connected to the means whereby the index wheel 40 is rotated.

10. The combination of an index wheel, key-controlled means for operating the same, a source of power for rotating said 45 wheel, said wheel having a cup or depression, a centrifugal brake rotating in said cup or depression, a pinion connected to said brake, and a movement-multiplying gear meshing with said pinion and connected to the means whereby the index wheel 50 is rotated, to cause the brake to rotate in the opposite direction from the index wheel.

11. In a computing machine, the combination with a master wheel and a brake 55 therefor, of an index or escapement wheel having an internal periphery to receive said brake, and a train of gearing to turn said wheel, said brake driven by some member of the train.

60 12. In a computing machine, the combination with a master wheel and an expanding brake, of an index or escapement wheel having an internal periphery to receive said expanding brake, and a train of gearing to turn said wheel, said brake driven by some

member of the train, the brake being driven in the opposite direction from the index wheel and at higher speed.

13. In a computing machine, an index or escapement wheel moving during the 70 computing operation and arrested to terminate the computing operation, a centrifugal brake for said wheel driven in the opposite direction and at considerably higher speed, and a train of gearing connecting 75 said escapement wheel and said brake.

14. In a computing machine, the combination with an index or escapement wheel and a train of gearing to drive said wheel, of means for arresting said wheel to terminate the computation, a brake effective only at high speeds to slow down said escapement wheel when it exceeds a given speed, and gearing for driving said brake to turn it in the opposite direction from said es- 80 capement wheel.

15. In a computing machine, the combination with an index or escapement wheel, of means for arresting said escapement wheel to terminate a computation, and a 90 brake geared to said escapement wheel and positively driven so as to tend to turn said escapement wheel in the opposite direction when the escapement wheel reaches excessive speed, said brake forming part of the train 95 of computing mechanism close to the escapement wheel.

16. In a computing machine, the combination with an index wheel and computing wheels adapted to be turned variable 100 amounts *seriatim* by variably turning said index wheel, of a drive shaft for said index wheel, means for exerting a torque on said drive shaft, and a brake automatically effective on said index wheel to tend to arrest it 105 when said torque is effective on it long enough to give it an excessive speed.

17. In a computing machine, the combination with an index wheel and computing wheels adapted to be turned variable 110 amounts *seriatim* by variably turning said index wheel, of a drive shaft for said index wheel, and a braking member adapted to bear against said index wheel and driven by said shaft in the direction opposite to 115 said index wheel, said braking member effective only when said index wheel turns at excessive speed.

18. In a computing machine, the combination of a power driving device for said 120 machine, an index wheel, means connecting said index wheel to said power driving device to turn said wheel in one direction to govern the extent of computation, and a friction brake, comprising members positively driven to tend to turn said wheel in the opposite direction when the speed of said wheel is excessive.

19. The combination with a series of 125 computing wheels, of indexing mechanism 130

for driving said computing wheels variable amounts to effect computing operations, a power drive effective on said mechanism, obstructing means for abruptly terminating the driving action of said indexing mechanism, and thereby determining the extent of movement of said computing wheels, and an automatic brake operating on said indexing mechanism to maintain the speed of drive of said computing wheels by said indexing mechanism below a destructive speed during a driving action, before an obstructing action.

20. The combination with a computing mechanism, of a positive drive for said com-

puting mechanism, a slip connection between said positive drive and said computing mechanism, normally slipping, but adapted to stop slipping and drive said mechanism, means for positively and suddenly arresting the computing mechanism, and a friction brake acting on said computing mechanism on the computing mechanism side of said slip connection, and automatically effective to slow said mechanism at a predetermined speed.

WALTER WRIGHT.
